ATTORNEY.

UNITED STATES PATENT OFFICE.

JAMES A. MURPHY, OF HOLYOKE, MASSACHUSETTS.

BASE-BALL BAT.

1,025,478.

Specification of Letters Patent.

Patented May 7, 1912.

Application filed October 3, 1911. Serial No. 652,514.

To all whom it may concern:

Be it known that I, JAMES A. MURPHY, a citizen of the United States of America, residing at Holyoke, in the county of Hampden and State of Massachusetts, have invented new and useful Improvements in Base-Ball Bats, of which the following is a specification.

This invention relates to an improvement 10 in a base-ball bat whereby the batter may obtain a better grip on the bat than is possible on bats as at present made.

The rules of the national game provide that all bats be made entirely of hard wood, 15 except that for eighteen inches from the handle end they may be wound with string, or provided with a granulated substance so that a better grip may be obtained than on the smooth wood.

20 It has been found from experience that where string is wound on the bat, or a granulated substance put thereon, it is continually wearing off and causing considerable bother to renew. For this reason a favorite 25 bat may be put out of commission at a critical point when a player most desires to use it.

The object of this invention is to provide 30 a bat which will always constantly be the same in giving a good grip for the batter and never getting out of order.

In the drawings forming part of this application,—Figure 1 is a partial cross section of a bat embodying the invention, Fig. 35 2 is a side view of the improved bat, Fig. 3 is a cross section of the handle, Fig. 2.

Referring to the drawings, in Fig. 1 the bat is made entirely of hard wood. A centrally bored hole *c* is provided in the bat 40 and small holes *b* lead from the exterior grooves *e* on the handle surface of the bat to said centrally bored hole. When the batter grasps the handle of the bat his hands sink slightly into the grooves *e*. The grooves 45 communicate with the centrally bored hole *c* by holes *b*. This structure forms a ventilated bat with a means for obtaining a good grip on the bat. As the bat is swung, a slight vacuum will be created in the centrally bored hole *c*, and the batter's hands

will be forced more tightly around the bat than would be the case if there were no openings to the atmosphere from those holes which are closed by the batter's hands.

An important feature of the invention is 55 the fact that by boring the central hole *c* a given distance, the weight of the bat will be distributed in a most convenient manner so that what ball players call the "hang" of the bat will be determined conveniently 60 when the bat is made. Thus a player who desires a bat with a particular "hang" may be accommodated very easily by distributing the weight at the proper point when the hole *c* is bored out,—all of which can be calculated precisely.

In the form of invention shown longitudinal grooves are made in the bat to form a good grip for the hands, and at the same time form a ventilated handle which will 70 prevent the batter's hands from slipping.

In this invention the longitudinal grooves give an exceptionally good grip on the bat while the radially bored holes extending to the atmosphere prevent the sting which usually accompanies the use of a grooved handle.

It is well known that when the smooth handle is used, the batter's hands frequently are so moist that he can not grasp the bat 80 firmly. This is evidenced by the fact that batters are continually rubbing their hands in the dirt just before stepping to their place.

With the bat herein disclosed, the balance 85 may be controlled conveniently, and a good grip obtained on the bat no matter what the condition of the batter's hands may be.

What I claim, is:—

A base-ball bat comprising a body portion 90 made entirely of hard wood, the handle portion thereof being provided with exterior grooves, a centrally bored hole in said bat, and small transverse holes leading from the bottom of said grooves to said centrally 95 bored hole.

JAMES A. MURPHY.
